HANDLE ASSEMBLY FOR WINDOW OPERATOR

Vern P. Fredricksen, Bayport, Minn., assignor to
Andersen Corporation, Bayport, Minn., a corpora-
tion of Minnesota

Filed Apr. 28, 1967, Ser. No. 6,878

Term of patent 14 years

(Cl. D10—11)

Fig. 1Fig. 2Fig. 3Fig. 4

FIG. 1 is an upper right front perspective view of a handle assembly for window operator, the handle being shown in closed position;

FIG. 2 is a front elevation;

FIG. 3 is a left side view with the handle in fully extended position, the right side being a mirror image thereof;

FIG. 4 is a bottom view thereof, the top view being substantially similar.

The broken lines are for illustrative purposes only.

I claim:

The ornamental design for a handle assembly for window operator, as shown and described.
